Specification of Letters Patent.

Patented Feb. 13, 1912.

Application filed January 6, 1911. Serial No. 601,193.

To all whom it may concern:

Be it known that I, ROSWELL A. LANCEY, a citizen of the United States, residing at Townsend, in the county of Middlesex and 5 State of Massachusetts, have invented certain new and useful Improvements in Leather-Board Machines; and I do hereby declare the following to be a full, clear, and exact description of the invention, such as 10 will enable others skilled in the art to which it appertains to make and use the same.

The invention relates to leatherboard machines and more particularly to mechanism for automatically severing and removing the 15 sheet of stock from the collecting roll after a predetermined thickness of stock has been collected upon the roll.

The object of the invention is to provide 20 novel and improved mechanism which will operate in a reliable and uniform manner to sever the stock after it has collected upon the roll to a predetermined thickness and to strip the severed stock from the roll without injury thereto.

To these ends the invention consists in the 25 features and combinations of parts herein-after described and referred to in the claims, the advantages of which will be obvious to those skilled in the art from the following 30 description of the machine embodying the invention.

The various features of the invention will be readily understood from an inspection of the accompanying drawings and the following 35 description of the construction illustrated therein.

In the drawings Figure 1 is a rear elevation of a leatherboard machine showing the preferred form of the invention applied 40 thereto. Fig. 2 is a partial side elevation looking toward the right in Fig. 1. Fig. 3 is a vertical sectional view showing the construction of the stripper plate. Fig. 4 is a vertical sectional view on line 4-4, Fig. 1. Fig. 5 is a partial longitudinal section 45 through the collecting roll. Fig. 6 is a detailed plan view of the mechanism for actuating the cutter. Fig. 7 is an elevation of the mechanism shown in Fig. 6, and Fig. 8 50 is a sectional view on line 8-8, Fig. 6.

The leatherboard machine illustrated in

the drawings is provided with the usual felt roll 1 about which the stock carrying felt band 2 travels and is also provided with a collecting roll or cylinder 3 which rests upon the felt roll 1 and is driven by frictional engagement therewith. The collecting roll is journaled in bearings formed in bearing blocks 4 which are mounted to slide vertically on the ways 5 in the usual manner. The 60 pulp stock carried by the felt 2 collects upon the roll 3 and successive layers of the stock are wound upon the roll until a cylinder of the desired thickness is formed thereon. During the collection of the stock upon the 65 collecting roll, the roll gradually rises, the bearings 4 sliding freely on the ways 5 as the thickness of the stock increases. As thus far described, the machine is of the usual construction and operates in the usual 70 manner.

In accordance with the present invention the stock collected upon the collecting roll is severed by a knife mounted within the roll which is automatically actuated when a pre-determined thickness of stock has collected 75 on the roll and the severed sheet of stock is stripped from the roll by a stripper plate which is automatically thrown into operation at the proper time.

In the construction shown in the drawings the knife blade 6 is secured upon a knife bar 7 which is mounted to move radially of the collecting roll. The knife bar is provided with ribs 8 which are fitted to slide 85 within guideways 9 formed in a supporting plate 10 which is secured within the collecting roll. The blade 6 normally lies within the periphery of the roll and is projected through a narrow slot in the periphery by a 90 series of toggles 11 connected to an actuating bar 12. The bar 12 is connected by means of a link 13 with a rod 14 which extends through the hollow journal of the roll and is connected at its outer end with the lower 95 end of a lever 15. The lever 15 is actuated at the proper time to project and retract the knife 6 by actuating mechanism which is controlled by the thickness of the stock collected upon the collecting roll. The supporting plate 10 is secured to the collecting roll by means of screws 101 which project 100

inwardly through counter-sunk holes in projecting shoulders 102 formed integrally on each end of the plate 10 and are threaded at 103 in the roll 3, as is clearly shown in Fig. 5. The supporting plate, the knife blade, the knife bar and the knife bar actuating mechanism which is mounted on the supporting plate can be removed as an entirety by loosening the screws 101 and drawing the plate 10 out through the longitudinal opening 104 (Fig. 4) in the roll 3. The knife and the mechanism for operating it, which is supported by the plate 10 within the opening 104 can thus be readily inserted and removed through said opening. The outer face of the plate 10 is a partially cylindrical surface of the same curvature as the roll 3 so that when the plate 10 is in place within the opening 104, it completes the peripheral surface of the roll 3 over the opening 104, leaving but a narrow slot at its side for the knife blade 6.

The mechanism for actuating the stock severing knife comprises a cam 16 arranged to engage a roll carried by the upper end of the lever 15. The cam is formed on a sleeve 17 which is mounted in a bearing 18 and loosely surrounds a continuously rotating shaft 19. The inner end of the sleeve 17 is provided with one member 20 of a clutch, the other member 21 of which is formed on a sleeve 22 which is keyed to turn with a slide on the shaft 19. The clutch members 20 and 21 are normally disengaged so that the cam 16 remains stationary in position to hold the stock severing blade retracted within the periphery of the collecting roll. When the stock is collected upon the collecting roll to a predetermined thickness, the clutch members are engaged and the cam 16 is given a single revolution, to advance and retract the knife 6, and then the clutch members are again disengaged and the mechanism which controls their engagement is reset.

In order that the mechanism for actuating the knife may be properly timed with relation to the rotation of the frictionally driven collecting roll, the shaft 19 is driven from the collecting roll. The mechanism for thus driving the roll in the construction shown comprises a sprocket chain 23 passing over a sprocket wheel on the end of the collecting roll shaft and over a sprocket wheel 24 which is connected with the shaft 19 through bevel gears 25. The sprocket wheels and gears are so proportioned that the shaft 19 makes one revolution for each revolution of the collecting roll.

The mechanism for controlling the engagement and disengagement of the clutch members 20 and 21 comprises a lever 26, the upper end of which is provided with a yoke embracing the clutch member 21 and carrying pins 27 for engaging the rear side of the

clutch member. The lower end of the lever is connected with a spring 28 which tends to force the clutch members into engagement. The clutch sleeve 22 is held in retracted position against the tension of the spring 28 by a latch 29 and resetting slide 30. The latch bar 29 engages a finger 31 connected to the rear side of the resetting slide. A pin 32 on the upper end of the lever 26 engages a lug 33 projecting from the front side of the slide.

When the latch bar 29 is raised the resetting slide 30 is released so that the slide and the clutch sleeve 22 are free to move toward the right in Fig. 6 under the influence of the spring 28. When this occurs, therefore, the clutch members are engaged and the knife actuating cam is rotated. When the latch bar 29 is raised to release the clutch sleeve 22 a supplemental latch 34 (Fig. 8) is pressed up against the under side of the finger 31 by the spring 35, the latch 34 being so arranged that it projects slightly beyond the engaging face of the latch bar 29. As the resetting slide 30 moves toward the right in Fig. 6 and left in Fig. 8, the finger 31 slides freely over the upper end of the latch 34. During the first half of the revolution of the cam sleeve 17, the resetting slide 30 is moved toward the left in Fig. 6 by a cam 36 secured to the sleeve. This movement of the slide carries the end of the finger 31 to the right of the latch 34 in Fig. 8, so that the latch rises into position to retain the resetting slide in its retracted position. At this time the latch bar 29 is still in its raised position. As the revolution of the cam sleeve and shaft 19 is completed, a cam 37 on the clutch sleeve 22 engages a pin 38 on the slide 30 and, the pin 38 being held fast retracts the clutch sleeve thus disengaging the clutch member and stopping the rotation of the knife actuating cam. A safety stop bar 39 actuated by the lever 26 may be arranged to engage a rib 40 on the back of the cam disk 16 to prevent the running forward of the cam after the clutch has been disengaged or to arrest the rotation of the cam in case the clutch members should not be disengaged for any reason. After the resetting slide has been retracted and latched in position by the latch 34, and the clutch members have been disengaged, the latch bar 29 moves down into position in front of the finger 31 pushing the latch 34 down below the finger 31, as indicated in Fig. 8. The resetting slide then moves forward slightly to bring its end over the supplemental latch 34 ready for the next cycle of operations.

In order that the knife actuating mechanism may be thrown into operation when a definite thickness of stock has been collected upon the collecting roll without regard to the number of revolutions of the collecting roll required, the latch bar 29 is so connected

with the collecting roll that it is operated by the upward movement of the roll. In the construction shown the devices connecting the latch and collecting roll comprise a bar 41, the ends of which are supported upon rods 42 rising from the bearing blocks of the collecting roll. This bar carries an adjustable screw 42, the upper end of which is arranged to engage a lever 43. The lever 10 is pivoted at one end to a fixed bracket 44 and is connected at the other end to the latch bar 29 by a link 45. The vertical position of the collecting roll and of the bar 41 depends upon the thickness of the stock collected upon the roll and by adjusting the screw 42, the connections between the roll and latch 29 may be adjusted to throw the knife operating mechanism into operation when any desired thickness of stock has been 15 collected upon the collecting roll. When the stock has been severed by the knife and removed from the roll, the roll returns into engagement with the felt roll 1, allowing the latch 29 to return into active position 25 and the knife actuating mechanism will be held out of action until the predetermined thickness of stock is again collected upon the collecting roll.

In order that the stock may be properly 30 and evenly cut by the radial movement of the knife 6, the roll 46 is so arranged that its periphery forms an abutment or cutting block for supporting the material against the outward thrust of the knife as the knife 35 is forced through the material. This roll may be cylindrical in form and may have its axis arranged parallel to the axis of the collecting roll in which case the knife will act to sever the stock simultaneously 40 throughout the length of the cylinder collected on the roll. It is preferred, however, to so arrange and shape the abutment roll that the knife and roll will co-act to secure a progressive cutting since this insures a 45 more even and uniform cut and requires less power in operating the knife. This construction and arrangement constitutes one of the features of the invention. In the construction shown the abutment roll 46 is arranged with its axis inclined somewhat to the axis of the collecting roll and the periphery of the abutment roll is concave longitudinally of the roll so that it will engage the edge of the knife progressively when the 50 knife is in its projected position. The roll 46 is journaled in bearings 47 carried by yokes 48 which are pivotally mounted on the ends of the collecting roll. The outer ends of the yokes 48 are connected with 55 supporting rods 49, the length of which may be adjusted by turn buckles 50 to vary the inclination of the roll or to bring it to the proper height with relation to the collecting roll. The roll is preferably driven from the 60 felt roll 1 by a belt 51.

After the cylinder of stock collected on the roll 3 has been severed by the cutter blade 6, the sheet of stock thus formed is stripped from the roll by a stripper or deflecting plate 52. The plate 52 is carried by arms 53 which are adjustably connected with supporting arms 54 secured to a rock shaft 55. The rock shaft 55 is mounted in brackets 56 secured to the bearing blocks 4 so that the stripper plate rises and falls with the collecting roll. The stripper plate is normally held in a raised or inactive position by a latch bolt 57 which underlies the front end of an arm 58 secured to the rock shaft 55, (Fig. 1). The latch bolt 57 is connected by a link 59 with the upper end of a lever 60, the lower end of which is arranged to be engaged and operated by the block 61 to which the lower end of the knife actuating lever is connected. When the lever 15 is rocked to actuate the knife, the lever 60 is operated against the tension of a spring 62 to retract the bolt 57. This puts the stripper in condition of permissive operation. At this time the slit formed in the stock in the collecting roll is not in position to receive the edge of the stripper plate and the plate should therefore be retained in its upper position until this slit comes under the edge of the plate and should 95 then be lowered to allow the edge of the plate to pass through the slit and engage the periphery of the collecting roll. Mechanism is, therefore, provided for thus controlling and timing the engagement of the 100 stripper plate with the roll. In the construction shown this mechanism comprises a timing cam 63 secured to the collector roll shaft and arranged to underlie a roll 64 which is mounted upon an arm 65 secured 105 to the shaft 55 which carries the stripper plate. When the pin 57 is retracted to release the stripper plate, the roll 64 rides on the cam 63 until the end 66 of the cam passes from under the roll and lowers the 110 stripper plate into engagement with the collecting roll. The cam is shaped to lower the stripper plate as the split formed in the stock by the knife comes into register with the edge of the plate. After the stripper 115 plate has been lowered it should remain in lowered position until the collecting roll has made a complete revolution so as to completely strip the sheet of stock from the roll and should then be raised into active 120 position to allow the fresh stock to collect upon the roll. After the roll 64 has passed off the end 66 of the cam 63, the cam 63 should therefore be rendered inactive until the collecting cylinder has made a complete 125 revolution and the latch pin 57 has been released ready to support the stripper plate when it is again raised. For thus rendering the cam 63 inactive and then resetting the parts so that the cam will act when the 130

stripper plate is again released, the following mechanism is provided. The roll 64 is carried by a stud 67 mounted to slide in the end of the arm 65. A finger 68 projects downward from the stud 67 into position to engage the cams 69 and 70. When the roll 64 passes off the end 66 of the cam 63, the finger 68 is brought into position to be acted upon by the cam 69. Before the 10 cam 63 comes into position to engage the roll 64, the cam 69 acting on the left side of the finger 68 shifts the roll toward the left so that it is out of the path of the cam 68. This movement of the roll brings it 15 into the path of a cam 71. The cam 71 is so arranged that it will lift the roll 64 and arm 65 as the rotation of the collecting roll is completed. Meanwhile the knife actuating lever 18 has been returned to normal 20 position and the latch bolt 57 has been released so that it snaps in under the end of the arm 58 when the cam 71 rocks the shaft 55 and raises the stripper plate. After the cam 71 has lifted the stripper plate, the 25 cam 70 engages the right side of the finger 68 and shifts the roll 64 into position above the timing cam 63 so that the engagement of the stripper plate will be properly timed when it is next released by the withdrawal 30 of the bolt 57.

In order that the stock may pass freely over the stripper plate without injury to the face of the stock or danger of the stock adhering or sticking to the plate, means are 35 provided for blowing a series of jets or ribbon of air between the surface of the plate and the stock. As shown, the stripper plate is hollow to form an air chamber 72 which is connected through a pipe 73 and valve 74 40 with a source of compressed air. A series of holes 75 are formed in the front face of the plate near its lower edge and are preferably inclined so that the air passing through them is directed obliquely toward the lower 45 edge of the plate. This air blast effectively prevents adhesion of the stock to the surface of the stripper plate and is also directed against the line of cleavage between the stock and the periphery of the collecting roll 50 so that the stock is stripped cleanly and uniformly from the roll.

The valve 74 which controls the supply of air to the stripper plate is normally held closed by a spring 76 acting on the valve rod 55 77. The valve is opened to supply air in the chamber within the stripper plate when the knife actuating mechanism is thrown into operation and is released to cut off the supply when the stripper plate is raised by a 60 cam slide 78 underlying the end of the valve stem 77. The cam slide 78 is connected to the link 79 with the upper end of the lever 60. When the lever 60 is actuated to withdraw the latch bolt 57 the cam slide 78 is 65 operated to open the valve 74. When the

latch bolt 57 snaps under the arm 58 as the stripper plate is raised the cam slide is returned to normal position thus closing the valve 74. A deflector roll 80 may be mounted above the stripper plate 72 to direct the 70 sheet stripped from the collecting roll toward the rear of the machine. The sheet stripped from the collecting roll is turned over as it is delivered by the stripper plate and roll 80 so that the surface that is next 75 to the collecting roll is uppermost as the sheet comes from the machine. A delivering table or conveyer may be provided for receiving the sheet as it comes from the machine. 80

While it is preferred to employ the specific construction and arrangement of the parts shown and described, it will be understood that this construction and arrangement is not essential to the broader features 85 of the invention and may be varied or modified without departing therefrom.

Having explained the nature and object of the invention, what is claimed is:—

1. A leatherboard machine, having, in 90 combination, a collecting roll, a knife within the roll, mechanism for actuating the knife, and a roll arranged with its axis at an inclination to the axis of the collecting roll and having a longitudinally concaved periphery for progressively cooperating with the edge of the knife in severing the stock, substantially as described.

2. A leatherboard machine, having, in 100 combination, a vertically moving collecting roll, a felt roll on which the collecting roll rests, a knife mounted in the collecting roll, an abutment roll against which the knife cuts, and mechanism for projecting and retracting the knife, substantially as de- 105 scribed.

3. A leatherboard machine, having, in 110 combination, a collecting roll, a knife for severing the stock on the roll, a stripper plate, and means for directing a blast of air between the plate and stock, substantially as described.

4. A leatherboard machine, having, in 115 combination, a collecting roll, a stripper plate, and means for directing a blast of air over the surface of the plate toward its active edge, substantially as described.

5. A leatherboard machine, having, in 120 combination, a collecting roll, a knife mounted in the roll, mechanism for actuating the knife, a stripper plate, a cam on the roll for timing the stripper plate, devices for rendering the cam inactive after it has thrown the stripper plate into operation, and means for throwing the stripper plate out of operation and for resetting said devices after the collecting roll has completed a single revolution, substantially as described.

6. A leatherboard machine, having, in 125 combination, a collecting roll, a knife mount-

- ed within the collecting roll, mechanism for actuating the knife controlled by the thickness of material collected on the roll, means for holding the stripper plate away from the 5 roll which are rendered inactive by the knife actuating mechanism, a timing cam on the roll for controlling the stripper plate when the holding devices are rendered inactive, devices for rendering the timing cam inactive after it is operated to move the 10 stripper plate toward the roll, and cams on the roll for returning the stripper plate to normally position and reset said devices after the roll has made a single revolution, 15 substantially as described.
7. A leatherboard machine, having, in combination, a collecting roll, means for severing the stock on the roll, a stripper plate for stripping the stock from the roll, a 20 series of holes along the stripper plate near its active edge, and means for blowing air through said holes, substantially as described.
8. A leatherboard machine, having, in combination, a collecting roll, means for severing the stock collected on the roll, a stripper plate for stripping the stock from the roll, an air chamber at the rear of the 25 plate, and holes leading from the air chamber to the surface of the plate which are inclined to direct the air toward the lower edge of the plate, substantially as described.
9. A leatherboard machine, having, in combination, a felt roll, a collecting roll resting on the felt roll, a knife mounted within the collecting roll, mechanism for actuating the knife comprising a clutch, a latch for holding the clutch out of operation, and devices between the collecting roll and latch 30 for actuating the latch, substantially as described.
10. A leatherboard machine, having, in combination, a felt roll, a collecting roll resting on the felt roll, a knife mounted within the collecting roll, mechanism for actuating the knife driven from the collecting roll including a clutch, a latch for holding the clutch out of action, and devices between the latch and collecting roll for withdrawing the latch through the vertical movement 35 of the roll, substantially as described.
11. A leatherboard machine having, in combination, a collecting roll, a knife for severing the stock on the collecting roll, a stripper and mechanism for releasing the stripper, and separate mechanism for timing the operation of the stripper, substantially as described.
12. A leatherboard machine having, in combination, a collecting roll, a knife for severing the stock on the roll, a clutch for throwing the knife into and out of operation controlled by the thickness of the material 45 on the collecting roll, a stripper for stripping the stock from the roll after it is cut, 50 means controlled by the clutch for holding the stripper out of operation, and means for determining the time of operation of the stripper with relation to the cut in the stock on the collecting roll, substantially as described.
13. A leatherboard machine having, in combination, a collecting roll, a knife for severing the stock on the roll controlled by the thickness of the material thereon, a stripper, a clutch for throwing the knife into operation and for putting the stripper in condition of permissive operation, and a timing device for controlling the time of the 55 operation of the stripper, substantially as described.
14. A leatherboard machine having, in combination, a collecting roll, a knife coöperating with the roll, means for operating the knife controlled by the thickness of the 60 material collected on the roll including a clutch, a stripper, a detent for supporting it out of operative position, connections between the detent and the knife for releasing the stripper, and a cam causing the stripper to engage the roll at the proper time to strip the severed stock therefrom, substantially as described.
15. A leatherboard machine having, in combination, a collecting roll, a knife coöperating with the collecting roll, mechanism for actuating the knife from the collecting roll including a clutch and clutch operating mechanism controlled by the thickness of the material collected on the roll, a stripper, 65 means for holding the stripper in inoperative position connected with the clutch controlling mechanism and released by the knife, a cam operatively connected with the stripper causing the stripper to engage the collecting roll at the proper time after the severing cut is made to engage the stock on the roll at the cut and to remain in contact with the roll for a complete revolution thereof, acting thereafter to lift the stripper out 70 of contact with the collecting roll, substantially as described.
16. A leatherboard machine having, in combination, a collecting roll, a knife coöperation with the collecting roll, mechanism for actuating the knife from the collecting roll including a clutch and clutch operating mechanism controlled by the thickness of the material collected on the roll, an abutment roll against which the knife operates, the 75 knife actuating mechanism being timed by its connection with the collecting roll to make its severing cut when it is opposite the abutment roll, a stripper, means for holding the stripper in inoperative position connected with the clutch controlling mechanism and released by the knife, a cam operatively connected with the stripper causing the stripper to engage the collecting roll at the proper time after the severing cut is made 80

to engage the stock on the roll at the cut and to remain in contact with the roll for a complete revolution thereof, acting thereafter to lift the stripper out of contact with the collecting roll, substantially as described.

17. A leatherboard machine having, in combination, a collecting roll, means for severing the stock on the roll, a stripper plate for stripping the stock from the roll, connections between the stripper and the severing means for putting the stripper in condition of permissive operation, and means for determining the timing of the stripper acting to hold it in contact with the collecting roll during a complete rotation thereof for thereafter lifting it therefrom and restoring it to the position of inoperativeness, substantially as described.

18. A leatherboard machine having, in combination, a hollow cylindrical collecting roll having a longitudinal opening therein, a stock severing knife, and mechanism for operating it located in said opening and adapted to be inserted and removed therethrough, substantially as described.

19. A leatherboard machine having, in combination, a collecting roll, a knife within the roll, mechanism for actuating the knife, an abutment roll against which the knife cuts located alongside of the collecting roll,

and mechanism controlled by the thickness of the material collected on the collecting roll for throwing the knife into operation, said knife and abutment roll having provision by virtue of which the knife is caused to cut across the roll progressively in severing the stock, substantially as described.

20. A leatherboard machine having, in combination, a collecting roll, a knife within the roll, mechanism for actuating the knife, and an abutment roll arranged with its axis inclined to the axis of the collecting roll so as thereby to cause the knife to cut progressively across the material in severing the stock, substantially as described.

21. A leatherboard machine having, in combination, a collecting roll, a knife mounted in the collecting roll, a stripper plate for stripping the severed stock from the collecting roll, and connected mechanism operating automatically upon the collection of a predetermined thickness of stock on the collecting roll to actuate the knife to sever the stock thereon and to cause the stripper plate to engage the collecting roll and strip the stock therefrom, substantially as described.
